UNITED STATES PATENT OFFICE.

JOHN D. HAGGARD, OF CHICAGO, ILLINOIS, ASSIGNOR TO HAGGARD & MARCUSSON COMPANY, OF CHICAGO, ILLINOIS, A CORPORATION OF ILLINOIS.

WIRE MATTRESS.

SPECIFICATION forming part of Letters Patent No. 739,171, dated September 15, 1903.

Application filed January 28, 1903. Serial No. 140,871. (No model.)

To all whom it may concern:

Be it known that I, JOHN D. HAGGARD, a citizen of the United States, residing at Chicago, in the county of Cook and State of Illinois, have invented certain new and useful Improvements in Wire Mattresses; and I do hereby declare the following to be a full, clear, and exact description of the invention, such as will enable others skilled in the art to which it appertains to make and use the same.

This invention relates to improvements in wire mattresses, and has for its object to provide a means for staying and stretching the woven fabric from time to time in maintaining the elasticity of mattresses indefinitely and prevent undue sagging.

In the drawings, Figure 1 is a plan of a mattress and frame to which it is attached. Fig. 2 is a broken-away exaggerated detail; and Fig. 3 is a transverse section on line 3, Fig. 1, looking in the direction indicated by the arrow.

A represent the companion side rails, and B B the end rails, composing the usual mattress-frame, all of which are properly secured together, the woven-wire mattress C being attached to the frame in the usual manner.

The companion stretching and strengthening cables 4 and 5 are located as at opposite sides of the mattress and are adapted to be run along thereunder. The ends of cable 4 are secured to the corners of the frame on the same side, as at a, and the ends of cable 5 to the corners on the opposite side, as at b. These cables are of a flexible make-up and are of a greater length than the distance between the points at which the ends of the same are fastened, so as to provide a slack position, which can be bowed inward under the mattress in the strained position illustrated in Fig. 1. In this position the part 6 of each cable, starting from the respective ends, runs at an angle diagonal to the side rails. The intermediate portion 7 of the cables between the diagonal parts run in a straight line and parallel the side rails. The cables are retained in this normal strained position by means of what may be termed "floating stay-rod" 8 and 9—that is, one for each cable—and which are located on the inner side thereof and parallel with the central

portion 7. These stay-rod are positioned lengthwise of the mattress, the free ends stopping short of the end rails of the frame. The rods are loosely inserted in the meshes of the fabric, Figs. 2 and 3, so that the position of the same may be changed from time to time in increasing the stretching strain as the fabric becomes slack from use. This is accomplished by shifting the position of the stay- rods inward in the direction of each other as often as may be necessary. The cables and stay-rod are connected by a number of open detachable links 10, which are disposed at intervals. The cables are not interwoven with the fabric, but press close against the underside thereof in the operation of stretching and stiffening the same.

The article is shown in its completed condition, Fig. 1, just as it is sent out of the factory, the fabric being stretched taut. It will be noted that the floating stay-rod are shown somewhat longer than the straight portions of the cables and extend past the junction with the diagonal parts and provide an A-shaped space g therebetween. After the fabric has become a little slack from use it may be stretched by simply shifting the end links 10 outward, which increases the strain on the fabric and cables and contracts the A space. When the fabric can no longer be stretched sufficiently to take up the slack by shifting the end links, all the links may be disengaged and the stay-rod moved to a new position, the links again inserted in their locking connection, and the fabric drawn taut. The stay-rod being set in a plain higher than that of the cables the connecting-links assume an inclined position, Figs. 2 and 3, with an upward pull on the cable and a lateral strain on the fabric. The stay-rod may also be moved endwise in the direction of either end of the frame from that of the position shown, as may be necessary in stretching different parts of the fabric, or one rod may be moved in the direction of the head end and the companion rod toward the foot end of the mattress, so that they occupy a diagonal position with reference to each other. In fact the stay-rod may be so positioned with reference to the cables as to exert a stretching action from any direction and the strain or

tension varied proportionate to the amount of slack in any particular place.

A greater number of cables and stay-rods may be used; but the number shown is ordinarily sufficient.

Having thus described my invention, what I claim, and desire to secure by Letters Patent, is—

1. A stretching and strengthening device 10 for woven-wire mattresses, comprising companion cables located at opposite sides of the mattress and running longitudinally thereunder and having their respective ends secured to the corners of the frame, stay-rods 15 anchored in the mattress toward the center thereof, and means for connecting said cables and rods in exerting a straining action in taking up the slack in the woven fabric, substantially as set forth.
2. A stretching device for woven mattresses, comprising companion cables located at opposite sides of the mattress and having their ends secured to the respective corners of the mattress-frame and running lengthwise 25 of and underneath the woven fabric, floating stay-rods inserted in the meshes of the fabric toward the center thereof, and detachable means for joining the cables and rods in their stretching position, substantially as set forth.
3. The combination with a wire mattress of 30 companion cables located at opposite sides thereof and having the ends secured to the respective corners of the mattress-frame and

running lengthwise of and bowed inwardly under the mattress, stay-rods removably inserted in the fabric toward the center, and means for joining the bowed portion of the cables and said rods in exerting a straining action, substantially as set forth.

4. The combination with a wire mattress, 40 of companion cables having their ends permanently secured to the respective corners of the mattress-frame and having a slack portion extending underneath the mattress from each side and running lengthwise thereof, 45 stay-rods loosely inserted in the woven fabric toward the center and the inclined links connecting said cables and stay-rods in a straining position and taking up the slack in the fabric, substantially as set forth.

5. The combination with a wire mattress, 50 of companion cables positioned along each side thereof and extending underneath the same at an angle, of companion stay-rods inserted in the meshes of the fabric from each side toward the center and adapted to be shifted to different positions with reference to the cables, and the movable links connecting the cables and stay-rods in their joint relation, substantially as set forth.

In testimony whereof I affix my signature in presence of two witnesses.

JOHN D. HAGGARD.
